UNITED STATES PATENT OFFICE.

JOSEPH R. SCHULTZ, OF ST. LOUIS, MISSOURI.

BOTTLE-CAP REMOVER.

1,110,720.

Specification of Letters Patent. Patented Sept. 15, 1914.

Application filed April 10, 1914. Serial No. 830,875.

To all whom it may concern:

Be it known that I, JOSEPH R. SCHULTZ, a citizen of the United States of America, residing in the city of St. Louis and State 5 of Missouri, have invented certain new and useful Improvements in Bottle-Cap Removers, of which the following is a full, clear, and exact description, reference being had to the accompanying drawing, forming 10 a part of this specification.

My invention relates to a bottle cap remover, and has for its object the production of a simple, efficient and inexpensive bottle opener which may be readily applied to a 15 counter, a wall, or other suitable support.

The preferred form of my invention comprises a bottle receiving member in the form of a ring provided with means for holding bottle caps and a retainer ring for securing 20 said bottle receiving member to a support.

Figure I is a front elevation of my bottle cap remover. Fig. II is a vertical section. Fig. III is a detail view of the bottle receiving ring. Fig. IV is a detail view of the retainer ring.

In the accompanying drawings: A designates a portion of a wall, or counter, or other suitable support provided with an opening for the reception of my bottle cap remover.

30 B designates a bottle receiving ring arranged in the opening in the support A and C is a retainer ring for securing the bottle receiving ring to said support. The rings B and C are preferably interlocked with each 35 other by means of external screw threads formed in the ring B and meshing with internal screw threads in the retainer ring C. The retainer ring C is provided with a flange 1 and fins 2 which are embedded in 40 the support A and the ring B is provided with a flange 3 embedded in the outer face of the support. In assembling my bottle cap remover the retainer ring C is first arranged in the opening in the support A, as shown in 45 Fig. II, and the ring B is then screwed into the retainer ring to firmly secure the two rings to the support A. The fins 2 prevent the retainer ring from turning.

The ring B is formed with a plurality of 50 lugs 4 having shoulders 5 adapted to engage the edge of a crown stopper or bottle cap, and stop lugs 6 adapted to limit the movement of the neck of a bottle in said

ring as shown by dotted lines in Fig. II. In removing a bottle cap the bottle may be 55 so positioned that its cap will be held by the lug 4 in the upper portion of the ring B and the stops 6 at the middle of said ring. A downward movement of the bottle will then result in the removal of the bottle cap. 60 If preferred the bottle cap may be engaged with stop lugs 6 and the lug 4 at the lower portion of the ring B and in this event the cap may be removed by moving the bottle upwardly, or the cap may be removed by 65 alternatively engaging the lugs 4 and by alternate upward and downward movement of the bottle.

I claim:

1. A bottle cap remover comprising a ring 70 adapted to be mounted in an opening in a suitable support, the said ring having a member interiorly thereof adapted to be engaged by a bottle cap, and a retainer ring fitted to said first mentioned ring by which 75 the latter is held in said opening.

2. A bottle cap remover comprising a ring adapted to be located in an opening in a support, the said ring having interiorly 80 thereof a plurality of spaced members for engaging a bottle cap, and a retainer ring fitted to said first mentioned ring to hold it in the opening of said support.

3. A bottle cap remover comprising a flanged ring adapted to be mounted in an 85 opening in a support, the said ring having interiorly thereof a member adapted to be engaged by a bottle cap, and a flanged retainer ring fitted to said first mentioned ring, the flanges of said rings being adapted 90 to impinge against the walls of the support in which the cap remover is mounted.

4. A bottle cap remover comprising a ring adapted to be mounted in an opening in a suitable support, the said ring being provided with an internal member adapted to be engaged by a bottle cap and with a stop 95 adapted to limit the movement of a neck of a bottle in said ring, and a retainer ring fitted to said first mentioned ring adapted to hold it in position in the opening in the support.

JOSEPH R. SCHULTZ.
